UNITED STATES PATENT OFFICE.

OSCAR D. HAPGOOD, OF MONTAGUE, MASSACHUSETTS, ASSIGNOR TO GOODELL-PRATT COMPANY, OF GREENFIELD, MASSACHUSETTS.

TOOL.

Application filed September 15, 1922. Serial No. 588,304.

To all whom it may concern:

Be it known that I, OSCAR D. HAPGOOD, a citizen of the United States of America, residing at Montague, Franklin County, Massachusetts, have invented new and useful Improvements in Tools, of which the following is a specification.

This invention relates to improvements in tools, and particularly to that class of tools in which motion is imparted from a crank handle to a rotatable tool-carrying spindle, the principal object of the invention being to provide improved motion - transmitting means between the handle and spindle whereby the spindle is capable of a great variety of adjustments for fast or slow, ratchet or direct motion, either in the same or the opposite direction from that of the handle.

20 A further object of the invention is to provide, in combination with a tool of the character set forth, a member adapted to serve the double function of a clutch and a ratchet.

25 With the foregoing and other objects in view, which will appear as the description proceeds, the invention consists in the novel features of construction and combination of parts which will be more fully described hereinafter and particularly pointed out in the claims.

In the drawings accompanying and forming part of this specification,

Figure 1 is a side elevation, partly broken away, of a tool embodying the present invention;

Fig. 2 is a fragmentary, sectional, side view taken at right angles to Fig. 1, the crank and driving gear being removed;

40 Fig. 3 is a central, longitudinal section of the tool shown in Fig. 1;

Fig. 4 is a fragmentary, side view of the tool looking from left to right of Figs. 1 and 3;

45 Fig. 5 is an inverted, plan view of the setting disk and capstan, showing the cam slot formed in the disk;

Fig. 6 is a transverse, sectional view taken on the line 6-6 of Fig. 3;

50 Fig. 7 is a transverse, sectional view taken on the line 7-7 of Fig. 3;

Fig. 8 is a perspective view of one of the double clutch members;

55 Fig. 9 is a perspective view of one of the parts of the setting plungers;

Fig. 10 is a perspective view of one of the single clutch members;

Fig. 11 is a perspective view of one of the pinion spacing sleeves; and,

Figs. 12 to 21 inclusive are diagrammatic, 60 side views illustrating respectively the different relative positions of the clutch members and pinions for each setting of the tool.

The same characters of reference designate the same parts in the different figures of the 65 drawings.

Referring to the drawings, 2 designates the housing or frame of the tool, within which is mounted for rotation a shaft or spindle 3, carrying at its lower end a chuck 70 4 of the usual construction for gripping a tool, the spindle being provided with a peripheral groove for the reception of the end of a set screw 5 threaded into the housing for retaining the spindle against lengthwise 75 movement.

Mounted for rotation upon the spindle 3 is a plurality of bevel pinions, shown herein as four in number, arranged in pairs at opposite sides of the longitudinal center of 80 the housing, each pair comprising an outermost pinion 6 and an innermost pinion 6^a. The pinions of each pair are maintained spaced apart by means of a sleeve 7, within which is located a double clutch member or 85 sleeve 8 having at each end face thereof a pair of oppositely disposed teeth 9 adapted to engage teeth or lugs 10 formed in the abutting faces of the pinions 6 and 6^a, the spacing sleeve 7 being of sufficient length to 90 permit the teeth of the clutch members to be held entirely out of engagement with both of the pinions. The teeth of these clutch members are so formed and disposed relatively to each other that when they are in 95 partial engagement with the teeth of either of the pinions they will act as ratchet teeth and permit the teeth of the pinions to slide over them in one direction, but when they are in full engagement with the pinion teeth they will lock the clutch member and pinion for movement together in both directions.

The clutch members 8 are provided with keys 11 adapted to engage longitudinal grooves formed in the spindle 3, whereby 100 said clutch members are rotatable with but said clutch members are rotatable with but slidable axially of the spindle.

For operating the double clutch members 8 into and out of engagement with their respective pinions, a slidible plunger is 110

provided for each clutch member, said plungers being adapted to slide in longitudinal openings formed in the housing. Each of the plungers is made up of two parts, a cylindrical part 12, having at its inner end a threaded portion of smaller diameter than the body of the plunger, and a part 12^a, shown best in Fig. 9, having a cylindrical portion provided in its end with a threaded opening for the reception of the threaded portion of the part 12, said part 12^a being semi-cylindrical at its inner end and provided on its flat side with a transversely extending stud 13 adapted to engage a cam slot 14 formed in the inner face of the setting disk 15, whereby, upon rotation of the disk, the plungers will be reciprocated. Each of the plungers carries a pair of radially extending spring members, most clearly shown in Fig. 6, each having a perforated stem 16 which is clamped between the plunger members 12 and 12^a, and extends through an opening 7^a, Fig. 11, in the wall of the sleeve 7, said stem merging into a bifurcated portion 16^a that engages a peripheral groove 8^a formed in the clutch member 8, the bifurcated portion of one member being bent or spread away from the other so that they engage respectively the opposite side walls of the groove 8^a, as shown in Fig. 3.

Between the two innermost pinions 6^a is disposed upon the spindle 3 a pair of single clutch members 19, each having at its outer end an annular flange 20 and a pair of oppositely disposed teeth 21, said teeth being extended inwardly of the clutch member or sleeve, as shown in Fig. 10, to form keys for engagement with the grooves in the spindle, whereby the single clutch members are rotatable with but slidable longitudinally of said spindle, said teeth being adapted to engage ratchet teeth 22 formed in the abutting face of the pinion 6^a. The single clutch members 19 are normally constrained toward each other and with their teeth out of engagement with the pinions by means of a coil spring 23, the opposite ends of which are hooked over a bent pin 24 projecting at the interior of the respective clutch members, the pins being so located that they and the coil spring find a clearance in one of the spline grooves of the spindle. Each of the flanges 20 of the clutch members 19 is seated within an opening formed in the frame, as shown in Fig. 3, and a capstan stud 25 is supported for rotation within an opening at right angles to and intersecting said first opening at one portion thereof, said capstan stud being provided with a radially extending, spring-pressed pawl or dog 26 that is adapted to bear on the flange of one of the clutch members when the capstan is rotated so as to bring said pawl into parallelism with the

spindle, whereby the clutch member is forced against the tension of the coil spring 23 into engagement with the ratchet teeth of its abutting pinion. In order to provide clearance to enable the pawl to spring out sufficiently far to engage the flanges of the clutch members, the wall of the opening in which the capstan is mounted is cut away at diametrically opposite points, as shown at 27 in Fig. 3. It will thus be seen that the pawl is normally retained in withdrawn position by contact of its outer end with the wall of the opening in which the capstan is carried, but when the capstan is rotated to bring the pawl into parallelism with the spindle, the niches 27 in the wall will permit the pawl to be protracted under the action of its spring 28 into contact with the flange of one or the other single clutch 19, as shown in Figs. 14 and 19, depending on whether the tool spindle is to be adjusted for right or left hand operation. The capstan 25 may be either formed integrally with the setting disk 15, or, as shown herein, secured thereto by providing a shouldered stem on the capstan adapted to fit a central opening in the disk, the disk being retained on the stem by means of a screw 29 seated in a countersunk opening in the disk and threaded into the capstan stem. In order to guard against any possibility of the capstan and disk rotating one relatively to the other, a groove and key connection, as shown at 30, Fig. 3, is formed between the disk and stem of the capstan, so that the pawl 26 and cam groove 14 are always retained in the same relative position. For retaining the capstan and disk against axial movement in the frame, a retaining pin 31, Fig. 4, having a portion adjacent to its head threaded into the wall of the frame in which the capstan is housed, said pin having a smooth portion at its inner end that extends transversely into an annular space 32 formed between the body of the capstan and the disk 15. In order to retain the capstan and setting disk in any "set" position, the capstan is provided with a plurality of peripheral depressions 33, Fig. 1, into which is adapted to project a spring-pressed ball which is located in the wall of the frame and retained therein by means of a screw 34, Figs. 1 and 4, threaded into the outer end of said opening, it being understood that there is one depression 33 for each adjustment of the tool spindle.

For driving the spindle, a pair of coaxial gears, shown herein as integrally connected together, is provided, the outer, larger gear 35 meshing with the outermost pinions 6 and the inner smaller gear 36 meshing with the innermost pinions 6^a, said gears being mounted for rotation on a stud 37, shown herein as solid with the frame, a crank handle 38 being secured to the gears by 130

means of a set screw 39, and having its free end bifurcated so as to engage the peripheral groove in the hub 40 of the gears. As herein shown, the gears are retained 5 against axial movement on the stud by means of a clip 41 which is secured by a set screw to the frame and extends a short distance over the back of the larger gear. It will be obvious that any other suitable means may 10 be employed for retaining the gears against axial displacement.

The frame 2 is attached by means of a tubular extension 42 to a breast portion or head 43, having the usual concave formation 15 and preferably provided with a flexible strap 44 bridging the ends thereof. The frame also carries the usual removable steadyng handle 45, suitably located at the side of the frame opposite the operating 20 crank handle.

The setting disk may be provided on its outer face with appropriate letters or other indicia indicating the operation of the tool which will result when the disk is rotated 25 to a certain position. For example, the index letter S may indicate slow direct movement of the tool spindle; F fast direct movement; SR slow ratchet; FR fast ratchet, etc.; while the frame may be marked with 30 the words "Right" and "Left" at points diametrically opposite with relation to the setting disk, to indicate the direction of the operative motion of the spindle according to whether the disk marking is set adjacent 35 to "Right" or "Left" on the frame, registering index lines being provided on the disk and frame for indicating the exact position of the parts for causing a given operation of the spindle.

40 The formation of the cam groove 14 in the setting disk and the position of the pawl 26 relative to said groove are such that, the following operations of the tool spindle will take place in response to the corresponding 45 setting of the disk, all of the said operations being brought about during one complete rotation of the disk:

Neutral position (Fig. 12).

50 The two double clutch members 8 between the pairs of pinions 6, 6^a, occupy a central position between said pinions, so as to be entirely out of engagement with either pinion. The pawl 26 is in retracted position, 55 so that the single clutch members 19 are both retained by the coil spring 23 out of engagement with the pinions 6^a. In this position, as will be readily seen, all of the pinions are free to rotate on the spindle, and 60 therefore rotation of the crank handle will produce no movement of the spindle.

2nd position (Fig. 2).

By a slight rotative movement of the set-

ting disk from neutral position, the cam 65 groove acts on the stud 13 of the lower plunger 12^a so as to carry the lower double clutch 8 into partial or ratchet engagement with the lowermost pinion 6, thus locking the spindle for rotation with the pinions in 70 one direction, all of the other parts remaining in neutral position. Rotation of the crank handle in forward direction, with the parts in this position, will produce a fast, forward or right-hand motion of the tool 75 spindle, while the backward or left-hand motion of the handle will cause the teeth of the lower double clutch to slide over the teeth of the pinion 6.

3rd position (Fig. 13).

80 Further rotative movement of the setting disk from the second position causes the cam groove to continue to act on the stud of the lower plunger so as to carry the 85 double clutch into full clutch engagement with the lower pinion 6, whereby the spindle is locked for rotation with said pinion in both directions, the other parts still retaining their relative neutral positions. In this position, the tool spindle follows the motion of the handle in both directions; that is to say, the spindle will have a fast, direct, forward motion when the handle is rotated in forward direction, and the motion of the 90 spindle will be reversed when the handle is reversed.

4th position (Fig. 14).

95 The disk is again rotated another step from the 3rd position, which rotation brings the pawl 26 into a position parallel with the spindle, whereupon the pawl is forced outward by its spring 28 into engagement with the upper single clutch 19, thus carrying the clutch into engagement with the 100 ratchet teeth of the upper inner pinion 6^a. In the meantime, the cam groove has exerted a slight retractive action on the lower plunger, thereby bringing the double clutch member 8 again into ratchet engagement with the lower pinion 6. The spindle is 105 thus locked for rotation with the lower pinion in one direction and with the upper, inner pinion 6^a in the opposite direction. With the parts in this position, a forward 110 movement is imparted to the spindle whether the handle is rotated forward or backward. In other words, on forward rotation of the handle, the lower clutch 8 locks pinion 6 to the spindle, thus imparting a fast, forward motion to said spindle, during which the upper single clutch 19 ratchets on the pinion 6^a. On reversing the direction of motion of the handle, the upper, single clutch locks the spindle to its pinion 6^a, thus imparting a slow, forward motion to the spindle, during 115 which the lower clutch 8 slides or ratchets over the teeth of the pinion 6.

5th position (Fig. 15).

The setting disk is rotated from the 4th position, thus retracting the pawl 26 from engagement with the upper single clutch 19, whereupon this clutch is withdrawn under the action of spring 23 out of engagement with upper, inner pinion 6^a. In the meantime the cam groove has exerted a further retractive action on the lower plunger and has brought the double clutch 8 into ratchet engagement with lower, inner pinion 6^a. Upon forward rotation of the handle, a slow, forward motion is imparted to the spindle, while upon reversal of the motion of the handle the teeth of the lower double clutch 8 will slide or ratchet over the pinion 6^a.

6th position (Fig. 16).

Continued rotation of the setting disk from the 5th position carries the lower double clutch 8 into full clutch engagement with lower, inner pinion 6^a. In this position, a slow, direct or forward motion will be imparted to the spindle when the handle is rotated in forward direction, the direction of rotation of the spindle being reversed when the handle is reversed.

7th position (Fig. 17).

The next step in the rotation of the setting disk from the 6th position carries the lower clutch 8 into neutral position, while the upper double clutch 8 is carried into ratchet engagement with the upper, outermost pinion 6. In this position, the spindle will have a fast, backward or left-hand motion when the handle is rotated forward, while when the handle is reversed, the pinion 6 slides or ratchets on the inclined teeth of the double clutch 8.

8th position (Fig. 18).

The next step in the rotation of the setting disk carries the upper double clutch 8 into full clutch engagement with the upper, outermost pinion 6, in which position the spindle is locked for fast backward motion when the handle is rotated in forward direction, and for forward motion when the handle is rotated backward.

9th position (Fig. 19).

The next step in the rotation of the setting disk withdraws the upper double clutch 8 back to ratchet engagement with upper, outermost pinion 6 and at the same time carries pawl 26 into position to engage the lower single clutch 19, thus forcing the latter into ratchet engagement with lower, innermost pinion 6^a. In this position, the spindle will be rotated in backward direction with a fast motion when the handle is rotated in forward direction, and will be

rotated backward with a slow motion when the handle is reversed.

10th position (Fig. 20).

The next step in the rotation of the setting disk causes the pawl 26 to be withdrawn from the lower single clutch 19, thus permitting the latter to be also withdrawn by its spring 23 from engagement with lower, innermost pinion 6^a. In the meantime, the upper double clutch 8 has been withdrawn from engagement with upper, outermost pinion 6 and carried into ratchet engagement with upper, innermost pinion 6^a. In this position, the spindle will have a slow, backward or left-hand motion when the handle is moved forward, and will ratchet or remain stationary when the handle is moved backward.

11th position (Fig. 21).

The next step in the rotation of the setting disk carries the upper double clutch 8 into full clutch engagement with upper, innermost pinion 6^a, thus setting the parts for slow, backward movement of the spindle when the handle is rotated forward, and slow, forward movement of the spindle when the handle is rotated backward.

The next step in the rotation of the setting disk carries the parts back into neutral position.

By means of the step by step rotation of the setting disk, therefore, ten distinct combinations of forward and backward motions are imparted to the tool spindle in response to the corresponding direction of rotation of the handle, namely:

<i>Rotation of handle.</i>	<i>Motion of Spindle.</i>	
Forward.	Fast forward.	105
Backward.	No motion (ratchet).	
Forward.	Fast forward.	
Backward.	Fast backward.	
Forward.	Fast forward.	110
Backward.	Slow forward.

While I have described in detail the struc-

ture herein illustrated, it is to be understood that I do not thereby limit my invention to the precise features of construction therein shown, as I am aware that many mechanical changes and modifications may be made therein without departing from the spirit and scope of the claims appended hereto.

Having thus described my invention, 10 what I claim is:

1. A tool, comprising, in combination, a frame, a spindle mounted for rotation in said frame, an operating handle mounted for rotation on the frame, gearing between 15 said spindle and handle and adapted to be actuated by the handle for rotating the spindle at different speeds, and means adjustable in one operation for changing the relative motion of the gearing and spindle 20 thereby to impart to the spindle alternately a fast motion and a slow motion when the handle is rotated forward and backward respectively.

2. A tool, comprising, in combination, a frame, a spindle mounted for rotation in said frame, an operating handle mounted for rotation on the frame, gearing between 25 said spindle and handle and adapted to be actuated by the handle for rotating the spindle at different speeds, and means adjustable in one operation for changing the relative motion of the gearing and spindle thereby to impart to the spindle alternately a fast motion and a slow motion in the same 30 direction when the handle is rotated forward and backward respectively.

3. In a tool of the class described, the combination of a rotatable spindle, means for changing the speed of rotation of said 40 spindle, means for changing the direction of rotation of the spindle, and means for simultaneously controlling said speed and direction changing means.

4. A tool, comprising, in combination, a frame, a spindle mounted for rotation in said frame, an operating handle mounted for rotation on the frame, gearing between 45 said spindle and handle adapted to be actuated by the handle for rotating the spindle, and means adjustable in one operation for changing the relative motion of the gearing and spindle thereby to impart to the spindle a backward motion during forward 50 rotation of the handle and a forward motion during backward rotation of the handle.

5. A tool, comprising, in combination, a frame, a spindle mounted for rotation in said frame, an operating handle mounted for rotation on the frame, change-speed 60 gearing between said spindle and handle adapted to be actuated by the handle for rotating the spindle means for changing the direction of rotation of the spindle, and 65 means for simultaneously controlling said

gearing and direction changing means thereby to impart to the spindle during one complete cycle of said controlling means the following motions in response to the forward and backward rotation of the handle respectively: a fast forward motion and a slow forward motion, a fast backward motion and no motion, a fast backward motion and a fast forward motion, a fast backward motion and a slow backward motion, 70 a slow backward motion and no motion, and a slow backward motion and a slow forward motion.

6. A tool, comprising, in combination, a frame, a spindle mounted for rotation in said frame, pinions mounted for rotation on said spindle, gears mounted for rotation on said frame and each in mesh with one of said pinions and adapted to impart a fast and a slow motion to the spindle, a 80 handle for operating said gears, and means simultaneously operable for locking one of said pinions for rotation with the spindle in one direction and another of said pinions for rotation with the spindle in the opposite direction thereby to impart to the spindle a fast and a slow motion respectively during the forward and backward rotation of the handle.

7. A tool, comprising, in combination, a frame, a spindle mounted for rotation in said frame, a plurality of pinions mounted for rotation on said spindle, gears mounted for rotation on said frame and each in mesh with one of said pinions, a handle for actuating said gears, a shiftable clutch sleeve mounted on said spindle for rotation therewith, said clutch sleeve having integral means at its opposite ends for engaging the respective pinions thereby to lock the pinions for rotation with the spindle, said means being adapted when the clutch member is in one position to lock one of the pinions for rotation only in one direction and when in another position to lock the pinion for rotation in the same and the opposite direction, and means for shifting said clutch member.

8. A tool, comprising, in combination, a frame, a spindle mounted for rotation in said frame, a plurality of pairs of pinions, the pinions of each pair being mounted for independent rotation on said spindle, gears mounted for rotation on said frame and each in mesh with one pinion of each pair, a handle for actuating said gears, a pair of double clutch members mounted on said spindle for rotation therewith and shiftable axially thereof one between the pinions of each pair, each of said clutch members having integral means at its opposite ends for locking the respective pinions for rotation with the spindle, and means for simultaneously shifting said clutch members.

9. A tool, comprising, in combination, a

frame, a spindle mounted for rotation in said frame, a plurality of pairs of pinions mounted for rotation on said spindle, gears mounted for rotation on said frame and each 5 in mesh with one pinion of each pair, a handle for rotating said gears, a double clutch member carried by said spindle for rotation therewith and shiftable axially thereof between the pinions of each pair, a 10 pair of single clutch members mounted for rotation with the spindle and shiftable axially thereof between the pairs of pinions, each of said double clutch members being adapted to lock either of its pinions for rotation with 15 the spindle in one direction, and each of the single clutch members being adapted to lock one of the pinions for rotation with the spindle in the opposite direction, and means for simultaneously shifting said clutch 20 members into operative position.

10. A tool, comprising, in combination, a frame, a spindle mounted for rotation in said frame, a plurality of pairs of pinions mounted for rotation on said spindle, each pair 25 comprising an outer and an inner pinion, a plurality of driving gears mounted for rotation on said frame and each in mesh with one pinion of each pair, a handle for actuating said gears, a double clutch member 30 carried by said spindle for rotation therewith and shiftable relatively thereto between the pinions of each pair, said clutch members and pinions having coöperating teeth adapted to lock the pinions for rotation 35 with the clutch members, a pair of single clutch members carried by said spindle for rotation therewith and shiftable relatively thereto between the inner pinions of the respective pairs, coöperating means carried 40 by said inner pinions and single clutch members for locking said pinions for rotation with their respective clutch members in one direction, means for shifting either of said double clutch members into engagement 45 with the outer pinion of its pair thereby to lock said pinion for rotation in one direction only and simultaneously shifting one of said single clutch members into engagement with the inner pinion of the other pair thereby 50 to lock the same for rotation in the opposite direction.

11. A tool, comprising, in combination, a frame, a spindle mounted for rotation in said frame, a plurality of pairs of pinions mounted for rotation on said spindle, each pair 55 comprising an outer and an inner pinion, a plurality of driving gears mounted for rotation on said frame and each in mesh with one pinion of each pair, a double clutch 60 member carried by said spindle for rotation

therewith and shiftable relatively thereto between the pinions of each pair, said clutch members and pinions having coöperating teeth adapted to lock the pinions for rotation with the clutch members, a pair of single clutch members carried by the spindle for rotation therewith and shiftable relatively thereto between the inner pinions of the respective pairs, coöperating teeth carried 65 by said inner pinions and single clutch members for locking said pinions for rotation with their respective clutch members in one direction, a reciprocable plunger for controlling the shifting movement of each of said double clutch members, a pawl for shifting said single clutch members into engagement with their respective pinions, and means for simultaneously operating said plunger and pawls to adjust the clutch members in proper position relatively to the 70 pinions thereby to impart to the spindle a predetermined motion.

12. In a device of the class described, the combination of a rotatable spindle, a pair of pinions mounted for independent rotation on said spindle, means for rotating said pinions at different speeds, a shiftable double clutch mounted on said spindle for rotation therewith between said pinions and adapted to engage either of the pinions for rotating the spindle in one direction, a shiftable single clutch also mounted on the spindle for rotation therewith and adapted to engage one of said pinions for rotating the spindle in the opposite direction, and means for shifting said clutches in unison.

13. In a device of the class described, the combination of a rotatable spindle, two pairs of pinions mounted for independent rotation on said spindle, means for rotating one pinion of each pair at a different speed from that of the other, a pair of shiftable double clutches mounted on said spindle for rotation therewith, one between the pinions of each pair, said clutches being adapted to engage either pinion of the respective pairs for rotating the spindle in one direction, a pair of shiftable single clutches also mounted upon the spindle for rotation therewith between the pairs of pinions and each adapted to engage one pinion of a pair for rotating the spindle in the direction opposite to the direction of rotation of the double clutch of the same pair, and means for shifting said clutches in unison thereby to simultaneously change the speed and direction of rotation of the spindle.

In testimony whereof I have signed my name to this specification.

OSCAR D. HAPGOOD.
